BUST SUPPORT

Rosaria Ciringione, Forest Hills, N. Y.

Application May 5, 1948, Serial No. 25,209

1 Claim. (Cl. 2—42)

1

The present invention relates to bust supports. The need for adjustable bust supports has led to designs which, while theoretically satisfactory, involve a multiplicity of parts, hence being inconvenient to wear, difficult to adjust, and relatively high in price. Other developments, while providing the desired adjustability, fail to give needed support. In a known form of breast support, for example, each breast pocket consists of two overlapping sections which are substantially triangular, with a curved draft, and are loosely connected together at their apices by a connecting strap linked to a shoulder strap, the latter by its upward pull tending to maintain the two sections in overlapping relation. None of the known bust supports of which I am aware, however, combines the features of simplicity, dependability, comfort and adjustability to a wide range of diverse forms of human breasts.

The general object of the invention, therefore, is to provide a bust support combining the above features of simplicity, comfort and adjustability.

Another object of the invention is to provide, in a bust support, breast pockets each having a non-yieldable supporting portion and a yieldable portion accommodating breasts of various sizes.

A further object of the invention is to provide, in a bust support having shoulder straps, means independent of said shoulder straps for holding adjacent sections of each breast pocket in overlapping relation.

The above and other objects will become apparent from the following description, reference being had to the accompanying drawing in which:

Fig. 1 shows a bust support according to the invention, embodied in a brassière being worn by the user;

Fig. 2 is an enlarged view of the brassière illustrated in Fig. 1, showing the rear portions thereof;

Fig. 3 shows a modified form of fastener adapted to be used in combination with the brassière of Fig. 1; and

Fig. 4 shows a bust support according to the invention incorporated in a foundation garment.

The brassière 10, Figs. 1 and 2, comprises a pair of breast pockets or cups generally indicated at 11 and 12, respectively, a band 13 and shoulder straps 14, 15 connecting the ends of band 13 with pockets 11 and 12, respectively. The band 13 comprises two side portions 16, 17, an elastic insert 18 having a doubled-up lower edge as indicated by stitching 19, and a non-elastic dart

2

portion 20 interconnecting insert 18 with pockets 11 and 12. The side portions 16 and 17 may terminate in non-elastic end portions 21, 22, respectively, carrying fastening means such as hooks 23 and eyes 24, end portion 22 being connected to side portion 17 by means of an elastic strap 25.

Each of the cups 11, 12 consists of a segmental portion 26, secured by its periphery to an arcuate cutout 27 of the band 13, and two roughly trapezoidal portions 28, 29 fastened at their bases, in slightly overlapping relation, to the radial edges of the circular segment 26. Portion 26 is preferably of the same non-elastic material that constitutes the portions 16, 17 and 20 of the band 13, while portions 28 and 29 may be made of lace as shown in the drawing.

An edge of each of the trapezoidal portions of flaps 28, 29 is secured to band 13 at a respective section 30, 31 of the arcuate cutout 27 which does not adjoin the segment 26. The upper ends of the opposite, free edges 32, 33 are connected by means of elastic straps 34, 35, respectively, with the arc sections 31, 30 of the band 13. strap 34 connected to flap 29 stretching across part of flap 28 and strap 35 connected to flap 28 stretching across part of flap 29.

It will be seen that straps 34, 35 tend to keep the edges 32, 33 of each breast pocket in overlapping relation throughout the length of these edges, by virtue of their engaging the uppermost, free corner of the flaps and tending to draw same toward the opposite section of the arcuate cutout.

Secured to the overlapping portions 28, 29 of each breast pocket 11, 12 are the ends of a non-elastic strap 36, 37, respectively. Strap 36 passes through a ring or eye 38 which also retains the doubled-up end 39 of shoulder strap 14, said end 39 terminating in a buckle 40 affording adjustability to strap 14. Similarly, strap 37 passes through a ring or eye 41, as does the doubled-up end 42 of shoulder strap 15 which terminates in buckle 43.

As will be clearly seen from Fig. 1, portion 28 of each cup 11, 12 firmly supports the breast while portions 28, 29 yieldably enclose the upper breast portion only, fitting snugly thereover by virtue of the resilient straps 34, 35. While the portions 26 are preferably non-elastic, their relative portion may be varied to some extent because of the resiliency of insert 18. Additional resiliency to fit varying girth is provided by the elastic strap 25,

while a plurality of rows of eyes 24 afford adjustability to the band 13.

A modification of the closure means 22 through 25, Fig. 2, is shown in Fig. 3. Here a pair of non-elastic strips of material 44, 45 are secured to the end of side portion 16 and are provided with spaced eyelets 46 to accommodate a pair of hooks 47, the latter being held by the doubled-up elastic ribbons 48, 49 secured to the end of side portion 17.

Fig. 4 shows the bust support according to the invention incorporated in a foundation garment, such as slip 59. Breast pockets 11, 12, band 13 and shoulder straps 14, 15 are in their same relative position as in Figs. 1 and 2, band 13 being, however, joined to the slip 50 along its lower edge 51.

Although the invention has been described with particular reference to certain specific embodiments shown in the drawing, it is to be understood that I do not desire to be limited to the particular forms described and illustrated except as so limited by the appended claim.

I claim:

A bust support comprising a pair of breast pockets, a band having two arcuate cutouts, a pair of shoulder straps each secured to a respective end of said band and extending toward a respective one of said breast pockets, each of said breast pockets comprising a lower segmental portion joined to said band along part of a respective cutout and further comprising a pair of roughly trapezoidal flaps arranged side by side, each of said flaps having a first edge joined to said segmental portion and a second, adjacent edge joined to said band along a remaining part

5
10

of said respective cutout, the edges of said flaps respectively opposite said second edges overlapping each other in a loose manner along a line substantially forming a continuation of the respective shoulder strap, said shoulder strap being provided with two extremities each engaging a respective one of said flaps, an elastic strap secured to the outer one of said flaps and stretched from a point adjacent the free corner of said outer flap across part of the inner one of said flaps toward the center of said band, and an elastic strap secured to the inner one of said flaps and stretched from a point adjacent the free corner of said inner flap across part of the outer one of said flaps toward the end of said band, said elastic straps being secured to said band adjacent said respective cutout.

ROSARIA CIRINGIONE.
